UNITED STATES PATENT OFFICE.

EDWARD K. BIXBY, OF CHICAGO, ILLINOIS.

FOUNTAIN-PEN.

1,109,033.

Specification of Letters Patent. Patented Sept. 1, 1914.

Application filed March 19, 1913. Serial No. 755,292.

To all whom it may concern:

Be it known that I, EDWARD K. BIXBY, a resident of Chicago, in the county of Cook and State of Illinois, have invented certain 5 new and useful Improvements in Fountain-Pens, of which the following is a full, clear, and exact description.

My invention relates to fountain pens embodying a magazine for carrying solidified ink or ink tablets, and has for its object to provide an improved construction of the same, as will be hereinafter more definitely pointed out and claimed.

In the drawings Figure 1 is a longitudinal section of a fountain-pen embodying the invention, the cap being shown secured to the lower end of the pen as is done when the pen is to be used. Fig. 2 is an elevation of the pen the cap being shown in section 20 and applied to inclose the pen. Fig. 3 is a perspective of the cap or magazine for holding the tablets.

The pen comprises a hollow-body *a* having an ink-chamber *a'* therein, and a nipple *b* carrying the grooved feeding-device *c* of usual construction and a pen point *d*. Nipple *b* is detachably secured by a screw-thread *b'* to the cylindrical body *a* of the pen. The upper end of the body and nipple *b* are tapered to receive a correspondingly tapered cap *e* which is adapted to inclose the pen point.

The lower end of the body *a* is provided with a solid exteriorly screw-threaded extension *f*, and a cup or magazine *g* for containing a number of ink-tablets *g'*, is correspondingly threaded and removably secured to the body by said thread. The periphery of said cup and the lower end of the body *a* 40 are tapered correspondingly to the nipple *b*

and upper end of the body *a*, so that the cap *e* may be placed on and frictionally held around the lower end of the body and over the magazine. The magazine as thus shown in Fig. 1, is thus formed to fit within the 45 cap. In refilling the pen, it is only necessary to unscrew the magazine *g* and take out one of the tablets and drop it into chamber *a'* after removing the nipple *b* and then the chamber may be filled with water. 50

The invention thus provides an improved fountain-pen which comprises a magazine or container for solidified ink or ink tablets and which is fitted or connected to the body of the pen. The magazine adds but little to 55 the length of the pen when the cap is over the pen-point and when the pen is in use; the magazine does not interfere with placing the cap on the body, because it slips over the magazine. 60

Having thus described the invention what I claim as new and desire to secure by Letters Patent, is,

A fountain pen, comprising a body having a liquid chamber therein extending substantially the length thereof, a nipple and pen body detachably connected to one end of said body, a solid exteriorly screw threaded extension at the end of said body opposite the pen body, a magazine having an 65 70 interior screw thread engaging said screw threaded extension, and a detachable cap adapted to fit over either the pen body or over said magazine and onto the said body at that end.

EDWARD K. BIXBY.
